BOAT CONSTRUCTION

Carl H. Clement, Jr., United States Army,
Fort Belvoir, Va.Application March 1, 1943, Serial No. 477,581
3 Claims. (Cl. 9—6)(Granted under the act of March 3, 1883, as
amended April 30, 1928; 370 O. G. 757)

The invention described herein may be manufactured and used by or for the Government for governmental purposes, without payment to me of any royalty thereon.

This invention relates to a method of constructing storm boats and more particularly to a boat in which transverse frames have been eliminated.

It is an object of this invention to provide a boat design which will maintain its shape particularly in the fore and aft direction and which will be able to withstand severe torsional loads which are carried through the beam formed by the bottom, sides and the inner floor.

It is a further object of this invention to provide a boat of this type of construction which is simple and consists of a relatively small number of parts.

It is still another object of this invention to provide a strong, lightweight boat designed for use with high speed motors which will withstand the shock of waves and even of beaching the boat at high speed.

These and other objects and advantages of the invention will become apparent upon a consideration of the following detailed description when taken in conjunction with the accompanying drawings, in which—

Fig. 1 is a side elevation of a boat embodying the principles of the invention;

Fig. 2 is a cross-sectional view taken along the line 2—2 of Fig. 1;

Fig. 3 is a cross-sectional view taken along the line 3—3 of Fig. 1;

Fig. 4 is a plan view of one-half of the boat;

Fig. 5 is an enlarged plan view of the stern of the boat;

Fig. 6 is a view in perspective of the completed boat in which the inner bottom has been broken away to illustrate the beam placement;

Fig. 7 is a longitudinal cross-section of the center of the boat; and

Fig. 8 is a longitudinal cross-section of one of the side beams.

Referring particularly to Fig. 6, it will be seen that there has been provided an outer bottom 10, an inner bottom 12, and side panels 14. The side panels 14 are attached to the bottom 10 and reinforced by oak chines 24. Acting as a spreader between the inner and outer bottoms and in longitudinal alinement, side beams 22 are provided, the exact construction of which will be described later.

A keel beam 20 is centered between side beams 22 and performs the dual function of a keel and a spreader. The outside bottom of the boat is fas-

tened rigidly to each of these three beams and also to the lower edge of the side panels 14. An inside bottom is then applied over the top of these beams and rigidly fastened to them. This inner bottom is then attached firmly to the side panels 14 of the boat and to the ledge 26 formed by gluing and screwing an oak strip to the side panel. It will be noted that there are no transverse members in the supporting frame of the boat.

At the stern of the boat the inner floor 12 is cut away to form the motor well 16. A sub-floor 17, and a well panel 19 are placed in position and, together with the inner sides of the side beams 22 and the stern board or panel 21, form a closed well.

The general shape of the boat will be clear from a consideration of Figs. 1 and 4 in which the floor level is indicated by the dotted line 28. It will be seen that there is provided a wide boat with a relatively blunt nose. This feature will lend stability to the boat and facilitate loading and unloading.

The construction of the side beams 22 will be clear from a consideration of Figs. 2 and 8, referring to which it will be seen that a hollow beam construction is provided. As a top spacer for the beam I prefer to use an oak strip 30. Attached on either side of the strip 30 are plywood sides 34, the top edges of which are straight lines and the lower edges of which conform to the longitudinal curvature of the boat at the position in which the beam is to be used. A lower oak strip 33 is fastened into place completing the formation of the beam.

It will be seen that the construction thus described provides a lightweight hollow beam which has been built up on the same general plan as a spar for an aeroplane. This type of construction combines great mechanical strength with extreme lightness.

Referring to Figs. 2, 3 and 7, it will be clear that the same general type of construction is used for the keel beam 20, except that the stern side panels 34 are partially cut away to form a support for the sub-floor 17 of the motor well. Similar oak spacer strips 30 and 33 are used to give the desired lightweight construction.

A boat constructed as described above obtains its transverse strength by means of the box beam formed by the inside and outside bottoms and the side panels. The hollow beams in this construction act primarily to keep the outside and inside beams spaced properly. However, their use makes it possible to divide the bottom into four watertight sections which will make the boat

harder to sink in case of puncture to the outside skin.

While I have described a single embodiment of my invention, it is to be understood that I do not wish to be limited to the particular details and assemblies illustrated since various modifications within the spirit of the invention will suggest themselves to those skilled in the art.

Having described my invention, what I claim as new and wish to secure by Letters Patent is:

1. A uni-directionally braced hull construction comprising inner and outer vertically spaced hull bottoms, side and stern panels affixed to said bottoms along their edges, said panels sealing the space between and coacting with said bottoms to form in effect a single box beam coextensive with the length of the hull and a framework disposed between and attached to the opposing faces of said bottoms, said framework being formed of a plurality of box beams aligned parallel to the longitudinal axis of said hull and dividing said single box beam into a series of longitudinally extending watertight compartments.

2. A uni-directionally braced hull construction comprising inner and outer vertically spaced hull bottoms, side and stern panels affixed to said bottoms along their edges, said panels sealing the space between and coacting with said bottoms to

form in effect a single box beam coextensive with the length of the hull and a framework disposed between and attached to the opposing faces of said bottoms, said framework being formed of a trio of equi-spaced box beams extending in parallelism longitudinally of the hull, the intermediate beam of said trio serving as a keel beam, said beams dividing said single box beam into a series of longitudinally extending watertight compartments.

3. A uni-directionally braced hull construction comprising inner and outer vertically spaced hull bottoms, side and stern panels affixed to said bottoms along their edges, said panels sealing the space between and coacting with said bottoms to form in effect a single box beam coextensive with the length of the hull and a framework disposed between and attached to the opposing faces of said bottoms, said framework being formed of a plurality of box beams aligned parallel to the longitudinal axis of said hull, each of said beams embodying upper and lower oak spacer strips affixed to the upper and lower edges respectively of a pair of laterally spaced plywood side pieces, said beams dividing said single box beam into a series of longitudinally extending watertight compartments.
